UNITED STATES PATENT OFFICE.

ELIHU C. WILSON, OF LOS ANGELES, CALIFORNIA.

WELL ELEVATOR.

continuation of application Serial No. 879,130, filed December 26, 1914. This application filed April 20, 1920. Serial No. 375,332.

To all whom it may concern:

Be it known that I, ELIHU C. WILSON, a citizen of the United States, residing at Los Angeles, in the county of Los Angeles, State 5 of California, have invented new and useful Improvements in Well Elevators, of which the following is a specification.

This invention relates to well elevators, commonly known as casing or pipe elevators. 10 It is the general object of this invention to provide an improved and more effective latching means for the relatively movable clamping parts of casing or pipe elevators. The latching mechanism which I herein 15 show, describe and claim is generally applicable to any of the usual types of casing or pipe elevators, but I show it in connection with that general type of elevator which has been patented to me on September 2, 1919, 20 No. 1,314,996, and I show it in detail as adapted to that type of elevator; although it will be readily understood that the invention is not limited to such detail.

This application is a continuation of my 25 application for well elevators filed December 26, 1914, Serial No. 879,130.

It is unnecessary here to state all of the objects, and corresponding features and accomplishments, of the invention in general, 30 because those will become more readily apparent from the following detailed description; but I may preliminarily mention that one of the primary objects of the invention is to provide a locking mechanism which is 35 easily and quickly operated, and also to provide a mechanism which cannot, by any ordinary operation of the elevator, or by any strain to which the elevator may ordinarily be subjected, become jammed, mutilated or 40 deformed, or in any manner become inoperative; and to provide such a locking mechanism that cannot, under any operative condition, be accidentally opened, or be forced open by any strains that are at any time imposed on the elevator. These and other 45 objects, and their corresponding features and accomplishments as embodied in the invention, will be most readily apparent from the following detailed description wherein I describe a preferred specific form of my latch 50 mechanism as applied to that particular type of elevator hereinbefore mentioned.

In said drawings Fig. 1 is a perspective showing the application of my latch mechanism to such type of elevator; Fig. 2 is an

end elevation of the elevator applied to the pipe; Fig. 3 is a plan of the elevator with the suspension links removed, and showing the pipe in place in the elevator; Fig. 4 is an enlarged detail section taken as indicated by line 4-4 on Fig. 3; Fig. 5 is an enlarged sectional detail, showing in upper plan the latch alone; Fig. 6 is an enlarged horizontal section, showing the operative parts of the elevator in closed position, said 60 section being taken just above the latch; Fig. 7 is a similar section showing the elevator in the act of being closed.

In the drawings I illustrate an elevator whose pipe embracing structure is made up 70 of a body A and a gate B, the two parts together forming the clamp which encircles, or substantially encircles the pipe. Gate B is hinged to body A on a vertical hinge pin 10; the other end of the gate being free to 75 swing to open and close the elevator. At the lower portion of its swinging end, the gate B is provided with a shoulder lug 12 adapted to ride over and rest upon a projecting lug 13 on body A; the lug 12 being 80 adapted to swing into the recess 14 above lug 13. The swinging end of the gate is thus positively supported vertically upon the body A at both ends against strains; the hinged end being vertically supported between hinge knuckles 15, as illustrated. The body is grooved or chamfered at 16 to receive the nose 17 of the free swinging end of gate B. All of this construction, is substantially, 85 in structure and operation, like that set forth 90 in my issued patent.

The whole elevator is suspended by the links 20 which connect with body A by passing between bifurcated extensions 21 and being held in place by block 22. This type of 95 suspension is set out and claimed in my application on hoists, Serial No. 835,924, filed May 2, 1914 patented June 1st, 1920, No. 1,341,967.

The latch member proper comprises a 100 shank 25 and a transversely extending head 26; these parts being preferably in the form of a T, so that the latch member, in its specifically preferred form, is referred to as a T-headed latch member. At its inner end 105 the latch shank 25 is mounted on a vertical pivot shaft 27. It may be adjustably mounted on that shaft and held in adjusted position by a set screw 28. Shaft 27 is mounted in extended lugs 29 on body A, one above 110

and one below the latch; and, projecting below the lower lug, is provided with a surrounding coiled spring 30, one end of which is connected at 31 to the body A and the other end at 32 to the shaft 27. This spring tends at all times to rotate the shaft 27 in the direction indicated by the arrows in Figs. 6 and 7. There is a stop lug 33 on the latch member, adapted to engage body A to limit rotation of the latch member in the direction indicated, making the limiting position of the latch member such as is shown in Fig. 7. There may also be another stop lug 34 on the opposite side of the latch member to engage the body A and to limit rotation in the opposite direction. Either this or an equivalent stop, or the resistance of spring 30 to movement of the latch toward the left in Figs. 6 and 7, or both, enable the action, hereinafter described, of opening the elevator and its removal from the pipe with a single movement of the latch.

It is to be noted that the latch head and shank are symmetrical with relation to a central radial line through them; and that the pivotal bearing surfaces at pin 27, the mounting of the shank on the pin, and the support of the pin, are all symmetrical with relation to that same radial line; so that a stress exerted on the head is transmitted in line through the shank and symmetrically through the bearings to the body A. The latch is thus "balanced" as regards stresses on it; and it is impossible to cause it to bind and be hard to move. The arcuate concentric engaging surfaces of the latch, (hereinafter described) not only make for good easily moving bearing surfaces free from excessive wear, but also aid in insuring the transfer of stress from the gate to the latch in a radial direction.

On the free swinging end of gate B there are two vertically spaced latch lugs 40, the upper one being preferably flush with the upper surface of gate B. The upper bearing lug 29 is also preferably flush with the upper surface of body A. When the elevator is closed shank 25 of the latch member is adapted to pass between the two latch lugs 40; and the head 26 lies behind, or outside of, the two lugs 40. In this position the head 26 lies against two shoulder surfaces 41, which stand inward of the lugs, in such a position that the latch head, when it has swung inwardly over the outer surfaces 40^a of the lugs, strikes these shoulder surfaces 41.

The outer surfaces 40^a of lugs 40 are formed so as to be concentric with the center of shaft 27, when the gate B is in closed position; and the inner surfaces of the head 26 of the latch member are also similarly concentrically formed, as shown at 26^a. When the gate is closed upon a casing or pipe, as it is swung inwardly, the curved

lateral face 26^b of the latch head first engages either the nose 17 of gate member B or the forward curved surfaces 40^b of the lugs 40 (depending upon the exact arrangement and conformation of the parts) and then rides over the forward surfaces 40^b of lugs 40 and is pushed out towards the left in Figs. 6 and 7 until the lugs 40 have passed the head. Then, just when the gate B reaches its final closed position, the head 26 swings in over the concentric outer lug surfaces 40^a, and brings up against the stop surfaces 41. Just enough clearance is provided to allow the latch head to swing over the lugs when the gate is in final closed position; but not enough clearance to make the gate appreciably loose relative to the body A.

When the latch is in the position shown in Fig. 6 it will be seen that no strain, however great it may be, which tends to force the gate B outwardly, in the direction indicated by the arrow in that figure, can have any tendency whatever to force the latch in a direction opposite to that indicated by the arrow on the latch in Figs. 6 and 7, and thus cannot, under any circumstances, have any tendency whatever to move the latch so as to loosen the gate or allow it to open. Furthermore, any incipient outward movement of the gate will, if anything, tend to throw surfaces 40^a out of concentricity in such a manner as to cause the latch head to be forced more solidly home against shoulders 41. Furthermore, if an excessively great strain is put upon the gate, tending to open it, such strain being large enough to deform the latch, it will be seen that such deformation will take place by bending the upper and lower ends of the latch head out toward the right in Fig. 4; and such bending will not at all render the device inoperative, because the latch head extends from the shank at right angle to the plane of movement of the shank rather than parallel to that movement. It will of course make the parts fit a little loosely, but it will not under any circumstances render them inoperative, or bend the parts to such a position as to change the operation as explained above.

In placing the elevator upon a piece of pipe, it is only necessary to place the body A around the pipe and then slam the gate shut, the latch acting entirely automatically. In removing the elevator from a pipe my latch is exceptionally handy. Of course the latch may be opened with one hand and the gate handle 50 used to open the gate with the other hand. But a very simple manner of removing the elevator from a piece of pipe, and the manner which is very much used by the man who is located on the platform in the upper part of a derrick, is merely to push against the latch head with the hand or with the foot, or with a stick of wood or

any other implement, pushing generally toward the left in Fig. 6. The first effect of this operation is to swing the latch around toward the left in Fig. 6. As soon as the latch has swung to the point where it releases the gate, further pushing upon the latch around to the left will then push the body A off the casing, swinging the body A on hinge pin 10 and thus opening the gate B. 5 The elevator may thus be opened, and pushed off the casing by a single simple operation. This operation, as will be readily recognized, depends upon the fact that the latch in its opening movement, moves, or 10 swings around, in the same general direction of movement or of rotation with relation to body A that the body A moves, or swings around with relation to the gate B to open the elevator; and upon the fact that 15 some resistance is opposed (the stop or the spring) to such movement of the latch relatively to the body A. It will be observed that the end of the latch 26 has a clear projection beyond the periphery of the support 20 so that, notwithstanding the fact that, as hereinbefore described, the latch will very positively lock the parts together, this projecting toe of the latch 26 may be readily engaged and thrown out of its locking position without the use of any special releasing 25 tool.

It is to be noted that the secure locking of the gate does not depend at all upon the position of the elevator upon the pipe, or depend at all upon the elevator maintaining its 30 position under the collar C of the pipe P. The elevator may slide up and down the pipe without affecting the latch at all; and vertical vibrations of the elevator and pipe 35 (which occur very frequently in pipe handling practice) cannot at all affect the security of the gate; due to the fact that the latch swings around horizontally and therefore cannot be affected by any vertical vibration. And, furthermore, accidental contact of the elevator while running vertically, with an external object, is much less apt to 40 open the horizontally moving latch than one which moves in any other direction.

50 It is to be noted that the latch is located, and connects to the body and gate, at points substantially below their upper edges. The gate is therefore held very effectively against any twisting or binding action that might otherwise occur; for instance, if the gate 55 were latched at its upper edge and lateral opening pressure were exerted on it at its middle or lower portions.

It is to be understood that my invention 60 is not limited to the exact details of the particular embodiment thereof which are illustrated in the accompanying drawings and described in the foregoing specification, except as such details are specifically recited 65 in the following claims. There can, of

course, be considerable variation in many of the details illustrated and described without departing from the spirit or scope of the invention, and such illustration and description are to be considered as merely illustrative and not restrictive of the broader 70 claims appended hereto.

Having described a preferred form of my invention, I claim:

1. In casing handling tools, the combination of a plurality of clamping and holding members hinged together and adapted to embrace between them a pipe or casing, and an oscillatory latch device pivotally connected with one of said members and adapted to 75 cooperate with the other of said members to hold said members in locked condition; said latch device comprising a shank provided with a head portion, the member with which said latch device is engaged being provided with spaced heads with which said latch device head is engaged and between which the shank thereof is received; said spaced heads being provided with seats to receive said latch device head to hold the member in 80 locked condition.

2. In casing handling tools, the combination of a plurality of clamping and holding members hinged together and adapted to embrace between them a pipe or casing, suspension means secured to one of said members, an oscillatory latch device pivotally connected with said member having a head adapted to be moved in an arcuate path to 85 cooperate with the other of said members to hold said members in locked condition, spring means urging said latch device in one direction, spaced lugs being provided on said last named member for cooperation 90 with said latch device head; said spaced lugs having arcuate portions over which the latch head may ride under the influence of 95 said spring means.

3. In casing handling tools, the combination of complementary clamping and holding members hinged together and constructed to define a bore for the reception of a casing, a spring urged oscillatory latch pivotally connected to one of the members and mounted to swing in a plane at right angles to the axis of the bore, and a head on the other member provided with a seat for engagement with the swinging end of the latch to hold the two members together, the nose of the latch being beveled, so that it will automatically be swung outwardly by engagement with the other member and then permitted to return to working position when the elevator is closed.

4. In casing handling tools, the combination of complementary clamping and holding members hinged together and constructed to define a bore for the reception of a casing, a spindle rotatably mounted on one of the members, an oscillatory latch rigid with the 125 130

spindle and projecting laterally therefrom, said latch having a beveled nose and being mounted to swing in a plane at right angles to the axis of the bore, a spring applied to 5 the spindle and normally holding the latch in operative position, stop means limiting the swinging movements of the latch and holding the beveled nose thereof in position for engagement with the other member to 10 swing the latch outwardly as the two members of the elevator are closed, and a head upon the other member provided with a seat adapted to interlock with the latch to lock the elevator in a closed condition.

15 5. In casing handling tools, the combination of a plurality of casing encircling members pivoted together near one end on a vertical pivot to swing relatively horizontally; and a latching device to hold the 20 swinging ends of said members together, embodying a swinging latch member pivoted to one of said members on a vertical axis to swing thereon in a horizontal plane, said latch member being located near the other 25 end of said member, adapted in one position to engage the other member and adapted to be released from said last mentioned member by movement in substantially the same direction with relation to said first 30 mentioned member as that in which the first mentioned member moves with relation to the last mentioned member in its swinging movement away from the last mentioned member, and means opposing said movement of the latch member with relation 35 to the member on which it is pivoted.

6. In casing handling tools the combination of a plurality of casing encircling members relatively movable to and from a position to surround a well casing; and latch means for holding said members together in closed position, embodying a latch supported on and pivoted to one member to swing thereon, the latch having a shank and a 40 laterally projecting head at its swinging end, the swinging bearings and support for the latch being symmetrically arranged with relation to a central radial line through the shank and the laterally projecting head being also so symmetrically arranged, and engaging the other member symmetrically with relation to a plane through said central radial line and at right angles to the swinging axis.

55 7. In casing handling tools, the combination of a plurality of casing encircling members relatively movable to and from a position to surround a well casing; and latch means for holding said members together in closed position, embodying a latch supported on and pivoted to one member to swing thereon, the latch having a shank and a laterally projecting head at its swinging end, the swinging bearings and support 60 for the latch being symmetrically arranged

with relation to a central radial line through the shank and the laterally projecting head being also so symmetrically arranged, and engaging the other member symmetrically with relation to a plane through said central radial line and at right angles to the swinging axis, and being also symmetrical with relation to a radial plane which is determined by said central radial line and said swinging axis.

8. In casing handling tools, the combination of a plurality of casing encircling members relatively movable to and from a position to surround a well casing; and latch means for holding said members together in closed position, embodying a latch supported on and pivoted to one member to swing thereon, the latch having a shank and a laterally projecting head at its swinging end, the swinging bearings and support for the latch being symmetrically arranged with relation to a central radial line through the shank and the laterally projecting head being symmetrically arranged, and engaging the other member symmetrically with relation to a plane through said central radial line and at right angles to the swinging axis, and being also symmetrical with relation to a radial plane which is determined by said central radial line and said swinging axis; the engaging surface of said head being arcuate in form and concentric about said swinging axis, and the other member having a latch engaging surface arcuate in form and concentric about said latch swinging axis when the members are in closed position.

9. In casing handling tools the combination of a plurality of casing encircling members relatively movable to and from a position to encircle a well casing; and latch means for holding said members together in closed position, embodying a latch supported on and pivoted to one member to swing thereon, the latch having a shank and a laterally projecting head at its swinging end, said head projecting in a direction substantially at right angles to the plane of movement of the latch, said head having an arcuate surface concentric with the swinging axis, and the other member having a corresponding arcuate surface adapted to be swung over and engaged by the arcuate latch surface.

10. In casing handling tools, the combination of a plurality of casing encircling members relatively movable to and from a position to encircle a well casing; and latch means for holding said members together in closed position, embodying a latch supported on and pivoted to one member to swing thereon, the latch having a shank and a laterally projecting head at its swinging end, the other member having a latch engaging surface, the latch head and said sur-

face engaging each other on an arcuate surface that is concentric with the swinging axis of the latch.

11. In casing handling tools, the combination of a plurality of casing encircling members pivoted together on a vertical pivot to swing relatively horizontally to and from a position to encircle a casing; and a latch device to hold the swinging ends of said members together in closed position embodying a latch pivoted on a vertical axis on one of said members to swing horizontally thereon, said axis being eccentric to the swinging axis between the two members, the other of said members having a latch engaging surface concentric with the latch axis when the members are in closed position, and the latch swinging into latching engagement with said concentric surfaces by swinging movement toward the swinging axis of the two members.

12. In casing handling tools, the combination of a plurality of pipe encircling parts pivoted together on a vertical axis near one end so that their other ends may swing relatively horizontally to and from a position to encircle a casing, and a swinging latch pivoted to one of said members on a vertical axis and engaging the other member near its swinging end on a vertical line of engagement.

13. In casing handling tools, the combination of a plurality of pipe encircling parts pivoted together on a vertical axis near one end so that their other ends may swing relatively horizontally to and from a position to encircle a casing, and a swinging latch pivoted to one of said members on a vertical axis and adapted to engage the other member on a vertical line of engagement, the vertical centers of the pivotal axis between the two members, of the pivotal axis of the latch, and of the vertical line of engagement of the latch with the second mentioned member, all being located between the upper and lower edges of the two members and at a substantial distance below their upper edges and the vertical length of such axis and line of engagement being of considerable vertical extent.

14. A casing handling tool comprising pivotally connected, opposed, clamping and supporting members movable to and from a position to surround and vertically support

an upright casing section; and a horizontally swinging latch on one member adapted to engage the other member when the parts are in closed relation, the engaging surfaces of the latch and last mentioned member being so formed as to prevent disengagement of the latch except by direct pressure thereon tending to turn said latch about its pivot, with the free end of the latch projecting radially from the member engaged thereby to permit it to be readily disengaged from its locking position.

15. In casing handling tools, the combination of a plurality of pipe encircling members hinged together at one end on a vertical pivot, the free ends adapted to be swung to and from each other to encircle a casing or pipe and to release the same; and means to hold the free ends together to hold the members about a pipe, comprising a latch pivoted to one member near its free end on a vertical axis and lying in the medial portion of the distance between the upper and lower edges of said members, said latch having a shank and a transverse head extending from the shank vertically, said head being symmetrically arranged about the central longitudinal axis of the shank, the other member having a latch head engaging lug near its free end and the head and lug engaging on an arcuate surface concentric with the latch pivot, the latch swinging into engagement with the lug by movement in a direction generally toward the pivotal interconnection of the two said members and swinging out of lug engagement by movement in the same general direction that the first mentioned member swings with relation to the second mentioned member to open up the space between the two members.

16. In casing handling tools, the combination of a plurality of casing encircling members hinged together for one member to swing horizontally with relation to another, and a horizontally swinging latch mounted on one member and adapted to engage and hold the other in closed position about the casing.

In witness that I claim the foregoing I have hereunto subscribed my name this 13th day of April 1920.

ELIHU C. WILSON.

Witness:

VIRGINIA BINGER.
